CLAIM

I claim the ornamental design for a light emitting diode, as shown and described.

DESCRIPTION

FIG. 1 is a perspective view of a light emitting diode showing my new design;

FIG. 2 is a top plan view of the light emitting diode according to the embodiment of FIG. 1;

FIG. 3 is a left side elevational view of the light emitting diode according to the embodiment of FIG. 1;

FIG. 4 is a front elevational view of the light emitting diode according to the embodiment of FIG. 1;

FIG. 5 is a right side elevational view of the light emitting diode according to the embodiment of FIG. 1;

FIG. 6 is a bottom plan view of the light emitting diode according to the embodiment of FIG. 1;

FIG. 7 is a rear elevational view of the light emitting diode according to the embodiment of FIG. 1;

FIG. 8 is a top plan view of the light emitting diode according to another embodiment of my new design;

FIG. 9 is a left side elevational view of the light emitting diode according to the embodiment of FIG. 8;

FIG. 10 is a front elevational view of the light emitting diode according to the embodiment of FIG. 8;

FIG. 11 is a right side elevational view of the light emitting diode according to the embodiment of FIG. 8;

FIG. 12 is a bottom plan view of the light emitting diode according to the embodiment of FIG. 8; and,

FIG. 13 is a rear elevational view of the light emitting diode according to the embodiment of FIG. 8.
